UNITED STATES PATENT OFFICE

2,641,776

BED TENT

Adolph V. Jensen, Council Bluffs, Iowa

Application November 12, 1949; Serial No. 126,859

8 Claims. (Cl. 5—113)

1.

My invention relates to a collapsible and portable tent that is complete with spring and mattress for accommodating one or more persons.

Tents have long been in use as one type of sleeping and living accommodations and generally they are used for such only on a temporary basis.

Sportsmen, campers, tourists and the like frequently carry tents with them not only for the savings in expense but for the convenience in being able to put up for the night at selected places where other accommodations may not be available, or desirable.

Since tents are chiefly used for short times and frequently for only one night stops it is apparent that the less work involved in transporting, erecting and collapsing them, the more satisfactory they will be. There are, however, various types of collapsible and portable tents available but even with these some additional conveniences for sleeping must be carried the tent after it is erected. Also, most present type tents usually are provided with a covering of canvas or the like which is generally satisfactory as protection from rain, or the like, but if there is no rain, such tents greatly restrict the movement of air within the tent. Also, if no tent is used for out-of-door sleeping when the weather permits, the sleeper is frequently troubled and disturbed by mosquitoes and the like.

It is therefore an object of my invention to provide a tent that can be easily and quickly extended or collapsed without requiring the placement of any loose or unattached parts, therefore, and that when extended is capable of sleeping one or more persons.

A further object of my invention is to provide a tent of the above class that when collapsed is formed into a compact portable unit that can conveniently be transported and that is particularly designed and adapted to be carried on the top of an automobile without danger of the interior thereof becoming soiled or disturbed because of its position on the automobile.

A still further object of this device is to provide a collapsible, portable tent that can be fitted with a standard size spring and mattress for sleeping one or more persons and which spring and mattress remain in position whether the tent is extended or collapsed, thereby providing a complete sleeping unit including bed and shelter in one compact unit.

A still further object of this device is to provide a collapsible, portable tent that is designed with a screen covering as well as a canvas cover-

2.

ing or the like so that at times the canvas covering may be removed and the tent will still provide a screen covering for the occupants as protection against mosquitoes or the like.

A still further object is to provide a bed tent that is capable of having a taut covering both in collapsed condition and extended condition.

A still further object of my invention is to provide a bed tent that has its bed part held in spaced relation to the supporting surface such as the ground.

A still further object of my invention is to provide a tent of the above classes that is economical in manufacture, efficient in use and durable in construction.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of this tent as seen from the rear, and ready for use.

Fig. 2 is a rear end view of this tent shown in Fig. 1.

Fig. 3 is a top view of this tent with portions of the tent covering cut away to more fully illustrate the construction and arrangement thereof.

Fig. 4 is an aside view of the roller latch taken on the line 4—4 of Fig. 3.

Fig. 5 is a rear end view of this tent in collapsed position.

Fig. 6 is a perspective view of this tent in collapsed position shown mounted on the top of an automobile for transporting, and.

Fig. 7 is a fragmentary perspective view of the front of my tent with a portion of the tent covering folded back to illustrate the arrangement and position of the screen-like covering therefore.

Referring to the drawings I have used the numerals 10 and 11 to designate two elongated frame bar members that are joined together in spaced relation near but not at their respective ends by the transversely arranged frame bar members 12 and 13 respectively, and this constitutes the frame for my tent. By securing the transverse bar members 12 and 13 near the end of the bars 10 and 11, each end portion of the bars 10 and 11 extends outwardly from the bars 12 and 13 respectively to form the projections 14, 15, 16 and 17 respectively, as shown in Fig. 1 and Fig. 3. The frame is horizontally positioned

and supported by a collapsible leg member 18 at each of the four corners thereof. A knee brace 19 is provided for each leg member 18, as shown in Fig. 2 and each leg can be collapsed or extended in the same manner as the well known card table legs.

Rotatably arranged adjacent the outside length of the frame bar 11 is the elongated roller member 20 that is provided on its rear end with the projecting rectangular shaft 21. A crank handle member 22 is secured to the end of the shaft 21 for manually rotating the roller 20 and the notched latch member 23 shown in Fig. 4 is pivotally secured to the outside of the transverse frame bar 13 so that the notch thereon can embrace the shaft 21 at times to prevent the rotation of the roller 20 as shown in Fig. 1 and Fig. 3.

The numerals 24 and 25 respectively designate two support rods of substantially the same length that are each pivotally secured at one end to the outside end portions respectively of the rear transverse frame bar 13, as shown in Fig. 2. A knee brace 26 attached at its respective ends to the frame bar 13 and support rod 25 permits the rod 25 to be collapsed as will later be described and also maintains it in substantially vertical position at times. The numeral 27 designates an elongated support rod that is bent slightly at its center portion and which is longer than the rods 24 and 25. The rod 27 is pivotally secured at one end to the frame bar 13 and is provided with the knee brace 28, as shown in Fig. 2. When the rod 27 is raised so that the brace 28 is locked in extended position, the free end of the support rod 27 will be at a point above and substantially midway between the frame bars 10 and 11. The numeral 29 designates an elongated bar brace member that is pivotally secured at one end to the rod 24 and similarly secured at its other end to the rod 27 below the bend therein, as shown in Fig. 2. The rods and braces 24-29 inclusive just described for the rear end of my tent have corresponding duplicate members similarly secured as described and arranged on the front frame bar 12 opposite each other. Like numbers have been given to like rods and braces on the front and rear of this device to more clearly explain the operation thereof in the explanation which appears later herein.

The numerals 30, 31 and 32 respectively designate horizontal support rods secured respectively to the free ends of each pair of rods 24, 27 and 25, as shown in Fig. 3. The numerals 33 and 34 designate a screen cover and canvas cover respectively which are arranged one over the other with the screen 33 on the bottom. At one end the screen and cover are secured to the roller 20 and can be rolled thereon or extended by rotation of the crank 22. The free ends respectively of the screen and cover are detachably secured to the outside of the frame bar 10 by any suitable means such as the snaps 35 and the body of both the screen and canvas cover is positioned over the tent structure, braces and rods heretofore described as shown in Fig. 1 and Fig. 5. The edge of the canvas cover 34 which forms the front of this tent is provided with the flap 36.

The numeral 37 designates a section of canvas or the like secured to the cover 34 in such a manner that when the tent is extended the portion 37 will form a front wall portion, as shown in Fig. 2. A window 38 is provided in the canvas section 37. This is not new and consists of a

screen portion having an outside flap covering that is well known in the art.

The numeral 39 designates an elastic cord secured at its respective ends to the frame bars 16 and 17 and slidably connected along its length to the top of the canvas front wall portion 37. This is accomplished by folding a portion of the top longitudinal edge of the front wall section 37 back onto itself and stitching it so that a passageway is formed along the edge through which the cord 39 passes. This serves to support the front wall 37 when the tent is erected as will later be described in detail. A similar cord 40 is secured to the frame bars 14 and 15 at the rear portion thereof. The cords 39 and 40 are positioned to pass over the horizontal rods 30-32 but under the screen 33.

A steel bed spring 41 may be secured to the frame bars 10-13 in any suitable manner as illustrated in Fig. 3. The spring 41, if desired, may have a cover 42 over which is placed a mattress 43 to provide comfortable sleeping accommodations for one or two persons.

Between the projections 16 and 17 there is secured a narrow floor portion 44 which is outside of the tent wall 37 when the tent is erected, as shown in Fig. 7. The numeral 45 designates a base board member secured to the front end of the floor 44 and extending upwardly at right angles therefrom. This base board has a plurality of spaced apart snaps 46 to which the flap 36 can be secured at times.

The numeral 47 designates the top portion of an automobile body, as shown in Fig. 6, which illustrates the convenient manner in which my tent can be detachably secured thereto by any suitable means such as the straps and hooks 48.

When thus constructed and arranged this tent can be used in the following manner: Fig. 5 illustrates this tent in collapsed position. However, it is only the legs, support rods, braces, screen and canvas covering that is collapsed. The frame of the tent, the bed spring, mattress and any bedding used remain in their normal ready for use position whether the tent is extended or collapsed.

To erect the tent after a suitable site has been chosen the legs 18 are opened and the respective knee braces are locked the same as for card table legs. The latch 23 is manually raised so it will be free of the shaft 21 and thus permit the screen 33 and canvas 34 to freely unwind from the roller 20. The long center support rods 27 are then manually raised until the knee braces 28 can be locked into place. At the same time the support rods 24 can be raised and the braces 29 will hold the rods 24 in substantially vertical position, as shown in Fig. 2. The rods 25 are manually raised and held in vertical position by the knee braces 26. Naturally as the rods 27, 24 and 25 are raised their respective horizontal rod members 30, 31 and 32 will engage the screen 33. The screen, and canvas 34 over it, will be unrolled from the roller 20 until the horizontal rods 30-32 are in place to form a wall tent, as shown in Fig. 1.

As this tent is erected the elastic cords 39 and 40 will be raised by the bars 30-32. The cord 39 will supplement the support for the front tent wall 37 and the cord 40 will act as additional support for the rear end portion of the screen and canvas covers. When the supporting rods and braces have been extended to provide the roof support for this tent the crank 22 can be rotated to remove any slack in the screen or

canvas cover that now constitutes the tent roof. Once the roof is taut the latch 23 is dropped into place over the shaft 21 and the tent is ready for use. As stated previously, the sleeping accommodations are ready for occupancy immediately and no unnecessary work or equipment is required for that purpose.

The window 38 can be open or closed by means of the flap covering as is desired.

Another novel feature of this tent is the removable screen and canvas covers. Should the weather be clear but freedom from mosquitoes or other insects desired, it is only necessary to unsnap the canvas 34 from the snaps 35 along the frame bar 10 and withdraw the canvas either partially, as shown in Fig. 7, or completely by pulling it over the tent and laying it by the roller 20. This will provide a maximum of free air within a screen enclosure. However, even the screen cover 33 can be unsnapped if desired while the tent occupant is provided with a comfortable bed raised off the ground.

To collapse the tent the various knee braces are merely unlocked to permit the roof supporting structures to return to the position shown in Fig. 5. As this occurs the latch 23 can be elevated and the crank 22 rotated to wind up the slack in the screen and canvas. The latch 23 is then replaced to prevent any accidental movement of the roller 20.

As the tent is collapsed it is obvious that there will be an overhang of the screen and canvas toward the front and back thereof. To handle this, I have provided the projections 14-17. At the front of the tent the floor 44 is between the projections 16 and 17, as shown in Fig. 3. It is on this floor that the overhang of the screen and canvas roof covering at the front of the tent will pile up when the tent is collapsed. The flap 36 is then extended over the baseboard 45 and secured to the snaps 46 as shown in Fig. 6. By this arrangement the flap 36 and floor 44 provide a covering for the front of this tent when mounted on an automobile or the like and thereby protects the tent from fluttering in the wind and also protects the bedding and tent interior from dust, dirt, rain or the like.

At the rear of the tent, when it is collapsed, the overhang of the roof covering will rest between the projections 14 and 15 and thus all portions of this tent are within its frame portions when it is being transported or stored.

Some changes may be made in the construction and arrangement of my bed tent without departing from the real spirit and purpose of my invention, and it is my intention to cover by my claims, any modified forms of structure or use of mechanical equivalents which may be reasonably included within their scope.

I claim:

1. In a cot-tent device having a frame member comprising two sides, a front and rear, outwardly extending projections on the front and rear respectively of said frame member, means providing a sleeping surface on said frame member and a cover member detachably secured to said frame member, a collapsible means for elevating and supporting said cover member comprising, a support rod pivotally secured at one end to each corner of said frame member, collapsible means for holding each of said support rods in vertical position at times, a pair of elongated support rods oppositely disposed on the front and rear of said frame; each said elongated support rod pivotally secured at one end to the

respective front and rear frame portions at a point between the ends thereof, collapsible means for holding said elongated support rods in upright position at times, a connecting support member extending between the free ends of said elongated support rods, a connecting support member between the free ends of each oppositely disposed first mentioned support rods, said device constructed so that when said cover supporting structure is extended to its operable condition said cover member will extend over all of said connecting support members with the support member on said elongated support rods extending longitudinally of the center of the tent and forming the apex of the roof, and said device when collapsed adapted so that portions of the cover can extend over and be secured to said projections on the frame member whereby the device can be protected from the elements when being stored or transported.

2. In a collapsible cot-tent device, a horizontal rectangular frame member supported on a plurality of collapsible legs, each end of two parallel sides of said frame member having outwardly extending projections, a floor member secured to said frame and extending to the ends of and between said projections, a roller member rotatably secured to one side of said frame, a means to facilitate the manual rotation of said roller member, a cover member wound about said roller member and adapted to be unwound therefrom so that one end thereof can be detachably secured to the opposite side of said frame member, a collapsible means for elevating said cover member and supporting it as a tent roof comprising, two support rods, one of said rods pivotally secured at one end to a rear corner of said frame member and the other rod pivotally secured at one end to a front corner of said frame member, a knee brace connecting each of said support rods to the respective rear and front portions of said frame member, a support member secured to the free ends of said support rods, a second set of support rods pivotally secured at one end to the other corners of the frame member at the rear and front thereof, a second support member secured to the free ends of said second set of support rods, a third set of support rods, each bent at the center and each longer than a rod of said first two mentioned sets, oppositely disposed respectively on the rear and front portions of said frame member at a point intermediate its ends and pivotally secured thereto, a second set of knee braces respectively connecting each of said third sets of support rods to the respective rear and front portions of said frame member, a pair of rod braces respectively pivotally secured at each end respectively to said second and third sets of support rods, a third support member secured to the free ends of said third set of support rods, an elastic cord arranged in the front and rear edges of said cover member and extending transversely over said third support member, said device constructed so that when said cover supporting structure is extended to its operable condition said cover member will extend over all three of said support members with the support member on said third set of support rods extending longitudinally of the center of the tent and forming the apex of the roof, and said elastic cords providing an additional means for holding the cover taut, and said device when collapsed adapted so that portions of the cover can extend over and be secured to said projec-

tions of the frame whereby the device can be protected from the elements when being stored or transported.

3. In a collapsible cot-tent device, a horizontal rectangular frame member supported on a plurality of collapsible legs, a roller member rotatably secured to one side of said frame, a means to facilitate the manual rotation of said roller member, a cover member wound about said roller member and adapted to be unwound therefrom so that one end thereof can be detachably secured to the opposite side of said frame member, a collapsible means for elevating said cover member and supporting as a tent roof comprising, two support rods, one of said rods pivotally secured at one end to a rear corner of said frame member and the other rod pivotally secured at one end to a front corner of said frame member, a knee brace connecting each of said support rods to the respective rear and front portions of said frame member, a support member secured to the free ends of said support rods, a second set of support rods pivotally secured at one end to the other corners of the frame member at the rear and front thereof, a second support member secured to the free ends of said second set of support rods, a third set of support rods, each bent at the center and each longer than a rod of said first two mentioned sets, oppositely disposed respectively on the rear and front portions of said frame member at a point intermediate its ends and pivotally secured thereto, a second set of knee braces respectively connecting each of said third sets of support rods to the respective rear and front frame member portions, a pair of rod braces respectively pivotally secured at each end respectively to said second and third sets of support rods, a third support member secured to the free ends of said third set of support rods; said device constructed so that when said cover supporting structure is extended to its operable condition said cover member will extend over all three of said support members with the support member on said third set of support rods extending longitudinally of the center of the tent and forming the apex of the roof.

4. In a cot-tent device having a rectangular frame member provided with a sleeping surface and a cover secured to said frame member, a collapsible means for elevating said cover member and supporting it as a tent roof comprising, two support rods, one of said rods pivotally secured at one end to a rear corner of said frame member and the other rod pivotally secured at one end to a front corner of said frame member, a knee brace connecting each of said support rods to the respective rear and front portions of said frame member, a support member secured to the free ends of said support rods, a second set of support rods pivotally secured at one end to the other corners of the frame member at the rear and front thereof, a second support member secured to the free ends of said second set of support rods, a third set of support rods, each bent at the center and each longer than a rod of said first two mentioned sets, oppositely disposed respectively, on the rear and front portions of said frame member at a point intermediate its ends and pivotally secured thereto, a second set of knee braces respectively connecting each of said third sets of support rods to the respective rear and front frame member portions, a pair of rod braces respectively pivotally secured at each end respectively to said second and third sets of support rods, a third support member secured to the free ends of said third set of support rods; said device constructed so that when said cover supporting structure is extended to its operable condition said cover member will extend over all three of said support rods extending longitudinally of the center of the tent and forming the apex of the roof.

port rods, a third support member secured to the free ends of said third set of support rods, an elastic cord arranged in the front and rear edges of said cover member and extending transversely over said third support member; said device constructed so that when said cover supporting structure is extended to its operable condition said cover member will extend over all three of said support members with the support member on said third set of support rods extending longitudinally of the center of the tent and forming the apex of the roof, and said elastic cords providing an additional means for holding the cover taut, and said device when collapsed adapted so that portions of the cover can extend over the front and rear of said frame and be secured thereto whereby the device can be protected from the elements when being stored or transported.

5. In a cot-tent device having a rectangular frame member provided with a sleeping surface and a cover secured to said frame member, a collapsible means for elevating said cover member and supporting it as a tent roof comprising, two support rods, one of said rods pivotally secured at one end to a rear corner of said frame member and the other rod pivotally secured at one end to a front corner of said frame member, a knee brace connecting each of said support rods to the respective rear and front portions of said frame member, a support member secured to the free ends of said support rods, a second set of support rods pivotally secured at one end to the other corners of the frame member at the rear and front thereof, a second support member secured to the free ends of said second set of support rods, a third set of support rods, each bent at the center and each longer than a rod of said first two mentioned sets, oppositely disposed respectively, on the rear and front portions of said frame member at a point intermediate its ends and pivotally secured thereto, a second set of knee braces respectively connecting each of said third sets of support rods to the respective rear and front portions of said frame member, a pair of rod braces respectively pivotally secured at each end respectively to said second and third sets of support rods, a third support member secured to the free ends of said third set of support rods; said device constructed so that when said cover supporting structure is extended to its operable condition said cover member will extend over all three of said support rods extending longitudinally of the center of the tent and forming the apex of the roof.

6. In a cot-tent device, a rectangular frame member provided with a sleeping surface, a cover secured to said frame, each end of two parallel sides of said frame member having outwardly extending projections, a collapsible means for elevating said cover member and supporting it as a tent roof comprising, two support rods, one of said rods pivotally secured at one end to a rear corner of said frame member and the other rod pivotally secured at one end to a front corner of said frame member, a knee brace connecting each of said support rods to the respective rear and front portions of said frame member, a support member secured to the free ends of said support rods, a second set of support rods pivotally secured at one end to the other corners of the frame member at the rear and front thereof, a second support member secured to the free ends of said second set of support rods, a third set of support rods, each bent at the center and each longer than a rod of said first two mentioned sets, oppositely disposed respectively, on the rear and front portions of said frame member at a point intermediate its ends and pivotally secured thereto, a second set of knee braces respectively connecting each of said third sets of support rods to the respective rear and front frame member portions, a pair of rod braces respectively pivotally secured at each end respectively to said second and third sets of support rods, a third support member secured to the free ends of said third set of support rods; said device constructed so that when said cover supporting structure is extended to its operable condition said cover member will extend over all three of said support rods extending longitudinally of the center of the tent and forming the apex of the roof.

each longer than a rod of said first two mentioned sets, oppositely disposed respectively, on the rear and front portions of said frame member at a point intermediate its ends and pivotally secured thereto, a second set of knee braces respectively connecting each of said third sets of support rods to the respective rear and front portions of said frame member, a pair of rod braces respectively pivotally secured at each end respectively to said second and third sets of support rods, a third support member secured to the free ends of said third set of support rods; said device constructed so that when said cover supporting structure is extended to its operable condition said cover member will extend over all three of said support members with the support member on said third set of support rods extending longitudinally of the center of the tent and forming the apex of the roof, and said device when collapsed adapted so that portions of the cover can extend over and be secured to said projections of the frame whereby the device can be protected from the elements when being stored or transported.

7. In a cot-tent device having a frame member comprising two sides, a front and rear outwardly projecting portion on the front and rear respectively of said frame member, means providing a sleeping surface on said frame member and a cover member detachably secured to said frame member, a collapsible means for elevating and supporting said cover member comprising, a support rod pivotally secured at one end to each corner of said frame member, collapsible means for holding each of said support rods in vertical position at times, a pair of elongated support rods oppositely disposed on the front and rear of said frame; each said elongated support rod pivotally secured at one end to a respective front and rear frame portion at a point between the ends thereof, collapsible means for holding said elongated support rods in upright position at times, a connecting support member extending between the free ends of said elongated support rods, a connecting support member between the free ends of each oppositely disposed first mentioned support rods, an elastic cord arranged in the front and rear edges of said cover and extending transversely over said connecting support member on the elongated support rods, said device constructed so that when said cover supporting structure is extended to its operable condition said cover member will extend over all of said connecting support members with the support member on said elongated support rods extending longitudinally of the center of the tent and forming the apex of the roof, and said elastic cord providing an additional means for holding

the cover taut, and said device when collapsed adapted so that portions of the cover can extend over and be secured to said projections on the frame member whereby the device can be protected from the elements when being stored or transported.

8. In a cot-tent device having a frame member comprising two sides, a front and rear, means providing a sleeping surface on said frame member and a cover member detachably secured to said frame member, a collapsible means for elevating and supporting said cover member comprising, a support rod pivotally secured at one end to each corner of said frame member, collapsible means for holding each of said support rods in vertical position at times, a pair of elongated support rods oppositely disposed on the front and rear of said frame; each said elongated support rod pivotally secured at one end to a respective front and rear frame portion at a point between the ends thereof, collapsible means for holding said elongated support rods in upright position at times, a connecting support member extending between the free ends of said elongated support rods, a connecting support member between the free ends of each oppositely disposed first mentioned support rods, an elastic cord arranged in the front and rear edges of said cover and extending transversely over said connecting support member on the elongated support rods, said device constructed so that when said cover supporting structure is extended to its operable condition said cover member will extend over all of said connecting support members with the support member on said elongated support rods extending longitudinally of the center of the tent and forming the apex of the roof, and said elastic cord providing an additional means for holding the cover taut.

40
